US00D678624S

(12) **United States Design Patent**
Willett

(10) **Patent No.:** **US D678,624 S**
(45) **Date of Patent:** **** Mar. 19, 2013**

(54) **COMBINED PET FOOD AND WATER DISPENSER**

(76) Inventor: **Shelley Sue Willett**, New Braunfels, TX (US)

(**) Term: **14 Years**

(21) Appl. No.: **29/427,156**

(22) Filed: **Jul. 15, 2012**

Related U.S. Application Data

(63) Continuation of application No. 12/620,521, filed on Nov. 17, 2009, now Pat. No. 8,245,665.

(51) **LOC (9) Cl.** **30-03**

(52) **U.S. Cl.** **D30/121; D30/132; D30/133**

(58) **Field of Classification Search** **D30/133, D30/121, 122, 124, 127, 128, 132; 119/51.01, 119/61, 51.04, 53, 57.91, 54, 53.5, 52.4, 119/51.11, 63, 61.2, 52.1, 57.5, 57.6, 51.13, 119/62, 75, 500, 501; 239/7, 687, 379, 397.5; 222/199, 181.1, 181.2, 185.1, 557, 156, 485, 222/486, 548, 555; 220/200, 227, 247, 262; 221/174, 185.1, 289, 295, 296, 559; 454/35; 209/270, 283, 244; 52/194, 192; 49/279, 49/344, 357; D34/28**

CLAIM

I claim the ornamental design for a combined pet food and water dispenser, as shown.

DESCRIPTION

FIG. 1 is a front perspective view of a combined pet food and water dispenser showing my new design.

FIG. 2 is a front view thereof.

FIG. 3 is a back view thereof.

FIG. 4 is a left side view thereof.

FIG. 5 is a right side view thereof.

FIG. 6 is a top view thereof; and,

FIG. 7 is a bottom view thereof.
